ACTUATOR CAP FOR A PRESSURIZED CONTAINER

Alvydas Velicka, Watertown, and Walter Makauskas, Prospect, Conn., assignors to The Riston Manufacturing Company, Naugatuck, Conn.

Filed May 13, 1974, Ser. No. 469,547

Term of patent 14 years

Int. Cl. D9—07

U.S. Cl. D9—258

FIG. 1

FIG. 2

FIG. 3

FIG. 4

FIG. 5

FIG. 6

FIG. 1 is a perspective view of an actuator cap for a pressurized container showing our new design;

FIG. 2 is a right side elevational view, the left side being a mirror image thereof;

FIG. 3 is a top plan view;

FIG. 4 is a bottom plan view;

FIG. 5 is a front elevational view; and

FIG. 6 is a rear elevational view.

We claim:

The ornamental design for an actuator cap for a pressurized container, substantially as shown and described.
